1

Latin name: *Malus domestica* Borkh.
Variety denomination: 'Gala 0502B'.

BACKGROUND OF THE VARIETY

'Gala 0502B' is a new and distinct variety of apple tree (*Malus domestica* Borkh), which variety originated as a limb sport mutation of 'Gala Royal Beau' (not patented). 'Gala 0502B' was discovered by the inventor in a cultivated orchard at Casaleone, Verona, Italy in 2010, and was selected for further observation because of the distinctive early coloration of its fruit. 'Gala 0502B' was first asexually propagated by chip budding in 2011 at Presina, Italy, and has since been observed to remain true to type over successive asexually propagated generations.

BRIEF DESCRIPTION OF THE VARIETY

'Gala 0502B' was first selected for its distinctive fruit, which is fully colored well before harvest. Fruit of 'Gala 0502B' is also distinguished by its solid purple overcolor and its readiness for harvest in a single pick. The shoots, leaves, petioles, young fruit and fruit stem of 'Gala 0502B' are also notable for their darker color as compared to parent 'Gala Royal Beau'. Table 1 sets forth a comparison of the fruit of 'Gala 0502B' to 'Gala Schnico' (U.S. Plant Pat. No. 27,577), 'Galaval' (U.S. Plant Pat. No. 19,909), 'Gala 0502' (U.S. Plant Pat. No. 28,235) and 'Gala'.

TABLE 1

Color Comparison of 'Gala 0502B' to Other 'Gala'-Type Varieties	
Variety	Color Characteristics
'Gala 0502B'	Early homogeneous coloring, solid purple, no stripes
'Gala Schnico'	Late non-homogeneous coloring, red solid flush with some stripes
'Galaval'	Red solid flush with few stripes on backside of fruit
'Gala 0502'	Early homogeneous coloring, red-purple, no stripes
'Gala'	Bright red flush over pale yellow ground

ABSTRACT

'Gala 0502B' apple is 'Gala' sport notable for its fruit, which attains a distinctive, deep purple-red color well before harvest. 'Gala 0502B' can be harvested in a single picking due to its early intense and even coloration.

5 Drawing Sheets**2**

One hundred percent of the fruit of 'Gala 0502B' can be harvested in a single pick, as compared to about fifty percent to eighty percent of 'Gala Schnico'.

5 BRIEF DESCRIPTION OF THE PHOTOGRAPHS

FIG. 1 shows trees of 'Gala 0502B';
FIG. 2 shows a flower of 'Gala 0502B';
FIG. 3 shows fruit and leaves on a 'Gala 0502B' tree;
10 FIG. 4 shows whole and sectioned fruit of 'Gala 0502B' (left and center) and 'Buckeye' (right); and
FIG. 5 shows fruit of 'Gala 0502B' (left), 'Buckeye' (center) and 'Galaval' (right).

Actual colors will vary with lighting conditions; color 15 characteristics of 'Gala 0502B' apple tree should therefore be determined with reference to the observations described herein below, rather than from these illustrations alone.

DETAILED BOTANICAL DESCRIPTION OF THE VARIETY

The attached illustrations and the following detailed 20 botanical description of 'Gala 0502B' apple tree are based on observations made and photos taken during the 2015 and 25 2016 growing seasons at Cornaiano, Italy of trees planted in 2013 on M9 T337 virus free rootstock (not patented). All colors are described according to The Royal Horticultural Society Colour Chart (2001). The characteristics described will vary somewhat depending upon cultural practices and 30 climatic conditions, and will vary with location and season. Quantified measurements are expressed as an average of 35 measurements taken from a number of individual plants of the new variety. The measurements of any individual plant or any group of plants of the new variety may vary from the stated average.

Tree:

Vigor.—Medium (typical of 'Gala'-type varieties).

Type.—Ramified.

Habit.—Drooping.

<i>Trunk diameter (at 30 cm above the graft).</i> —2.5 cm+/-0.2 cm.		Sepals:
<i>Bark texture.</i> —Smooth.		<i>Quantity.</i> —5.
<i>Bark color.</i> —Grey-brown 199A.		<i>Color.</i> —Green 142B.
<i>Type of bearing.</i> —On spurs and long shoots.	5	<i>Shape.</i> —Pointed, triangular.
Branch (fruiting branches located at around 1 m above the graft union):		<i>Margin.</i> —Smooth.
<i>Length.</i> —70 to 100 cm.		Leaves:
<i>Diameter.</i> —1 cm+/-0.1 cm at 5 cm from the stem.	10	<i>Shape.</i> —Elliptic.
<i>Crotch angle.</i> —110 degrees+/-10 degrees.		<i>Length.</i> —Up to 12 cm.
<i>Bark color.</i> —Greyed-green 197A.		<i>Width.</i> —Up to 5 cm.
<i>Lenticel length.</i> —0.14 cm+/-0.05 cm.	15	<i>Blade margin.</i> —Serrate.
<i>Lenticel color.</i> —Yellow-white 158A.		<i>Apex.</i> —Acute.
<i>Lenticels density.</i> —5+/-2 per cm ² .		<i>Base shape.</i> —Rounded.
One year old shoot:		<i>Division.</i> —Simple.
<i>Length.</i> —50 cm+/-10 cm.		<i>Arrangement.</i> —Alternate.
<i>Color.</i> —Greyed-purple 183A.		<i>Venation.</i> —Pinnate.
<i>Pubescence.</i> —Very weak.		<i>Vein color.</i> —Upper surface green 139C; lower surface red-purple 59A at base, fading to green 139D at apex.
<i>Thickness.</i> —0.5 cm+/-0.1 cm.	20	<i>Color of upper surface.</i> —Green 139A.
<i>Internode length.</i> —3.5 cm+/-0.5 cm.		<i>Color of lower surface.</i> —Green 139C.
<i>Lenticel density.</i> —12+/-2 per cm ² .		<i>Attitude in relation to shoot.</i> —Outward.
Flower buds:		Petiole:
<i>Quantity per spur.</i> —6 per spur.		<i>Length.</i> —4.3 cm+/-0.2 cm.
<i>Shape.</i> —Oval.	25	<i>Diameter.</i> —1.5 mm+/-0.1 mm.
<i>Length.</i> —0.6 cm.		<i>Color of upper surface.</i> —Red-purple 59A.
<i>Diameter.</i> —0.4 cm.		<i>Color of lower surface.</i> —Red-purple 59A.
<i>Color.</i> —Greyed-purple N187A.		Fruit:
Flowers:		<i>Quantity per cluster.</i> —Up to 5.
<i>Diameter of fully open flower.</i> —5 cm+/-0.2 cm.	30	<i>Diameter.</i> —77 mm+/-7 mm.
<i>Relative position of petal margin.</i> —Not touching.		<i>Weight.</i> —210 g+/-30 g.
<i>Number per cluster.</i> —5 plus king flower.		<i>General shape in profile.</i> —Conic.
<i>Date of first bloom.</i> —April 10.		<i>Position of maximum diameter.</i> —Upper 50% in profile.
<i>Date of full bloom.</i> —April 17.		<i>Ribbing.</i> —Absent or weak.
<i>Pollination requirement.</i> —Pollenizer required ('Fuji', 35		<i>Crowning at calyx end.</i> —Moderate.
'Red Delicious', 'Granny Smith').		<i>Aperture of eye.</i> —Closed.
Petals (all measured on king flower):		<i>Length of sepal.</i> —Long, 0.5 cm+/-0.1 cm.
<i>Number per flower.</i> —5.		<i>Bloom of skin.</i> —Medium.
<i>Shape.</i> —Oval.	40	<i>Greasiness of skin.</i> —Absent.
<i>Length.</i> —2.4 cm+/-0.2 cm.		<i>Background color of skin.</i> —Not visible.
<i>Width.</i> —1.4 cm+/-0.2 cm.		<i>Amount of over color.</i> —100%.
<i>Apex.</i> —Round.		<i>Over color of skin.</i> —Purple N79B.
<i>Base.</i> —Pointed.		<i>Intensity of over color.</i> —High.
<i>Margin.</i> —Smooth.		<i>Pattern of over color.</i> —Solid flush.
<i>Color of upper surface.</i> —White NN155C with red 54C 45		<i>Amount of russet around stalk cavity.</i> —Absent or small.
veins.		<i>Amount of russet on cheeks.</i> —Absent.
<i>Color of lower surface.</i> —White N155C with red 54B		<i>Area of russet around eye basin.</i> —Absent.
veins.		<i>Length of stalk.</i> —2.1 cm+/-0.2 cm.
Stigma:		<i>Thickness of stalk.</i> —0.3 cm+/-0.1 cm.
<i>Position.</i> —Above anthers (like 'Golden Delicious').	50	<i>Depth of stalk cavity.</i> —1.4 cm+/-0.2 cm.
<i>Size.</i> —Diameter 0.08 cm+/-0.1 cm.		<i>Width of stalk cavity.</i> —1.6 cm+/-0.2 cm.
<i>Color.</i> —Yellow 5A.		<i>Depth of eye basin.</i> —Shallow, 0.7 cm to 1 cm deep.
Style:		<i>Width of eye basin.</i> —2.3 cm+/-0.2 cm.
<i>Size.</i> —Length 1.0 cm+/-0.1 cm.	55	<i>Firmness of flesh.</i> —Medium, 6.5 kg per cm ² .
<i>Color.</i> —Yellow-green 145A.		<i>Flesh texture.</i> —Crisp.
Ovary:		<i>Aroma.</i> —Sweet.
<i>Size.</i> —Length 0.5 cm+/-0.1 cm.		<i>Juiciness.</i> —High.
<i>Color.</i> —Yellow-green 144A.		<i>Brix.</i> —14 to 15 ° Brix.
Anthers:		<i>Flesh color.</i> —Yellow 10D.
<i>Quantity.</i> —10+/-2.	60	<i>Number of lenticels.</i> —5+/-2 per cm ² .
<i>Size.</i> —Length 0.7 cm+/-0.1 cm.		<i>Size of lenticels.</i> —Large, up to 3 mm diameter.
<i>Color.</i> —Yellow 10A.		<i>Aperture of locules.</i> —Moderately open.
Pedicel:		<i>Stem color.</i> —Brown 200B.
<i>Length.</i> —2.8 cm+/-0.2 cm.	65	
<i>Diameter.</i> —0.1 cm+/-0.02 cm.		
<i>Color.</i> —Yellow-green 145A.		

US PP30,511 P3

5

6

Seeds:

Quantity per fruit.—Up to 2 per chamber, up to 10 per fruit.

Shape.—Pointed.

Length.—0.8 cm+/-0.1 cm.

Breadth.—0.45 cm+/-0.1 cm.

Color.—Greyed-orange 177A.

Harvest:

Time for harvest.—Mid-August, similar to other mid-season 'Gala' varieties.

Number of picks.—1.

Amount of fruit produced per tree per harvest.—20 kg+/-2 kg.

Disease resistance/susceptibility.—None noted; same as other 'Gala' varieties.

Market use.—Fresh.

Storageability.—Up to 9 months in controlled atmosphere storage.

I claim:

1. A new and distinct apple tree, substantially as described and illustrated herein.
